UNITED STATES PATENT OFFICE.

SAMUEL G. WORTON, OF DUQUESNE, PENNSYLVANIA.

REGENERATIVE FURNACE.

Application filed October 27, 1931. Serial No. 510,956.

To all whom it may concern:

Be it known that I, SAMUEL G. WORTON, a citizen of the United States, and resident of Duquesne, in the county of Allegheny and State of Pennsylvania, have invented certain new and useful Improvements in Regenerative Furnaces, of which the following is a specification.

This invention relates to the construction of regenerative furnaces, and more particularly to the construction and arrangement of the flues which connect the ports located at each end of such furnaces with the furnace regenerator chambers.

In the operation of regenerative furnaces, considerable quantities of the finely divided solids in suspension in the waste gases or products of combustion are carried from the furnaces through the ports into the regenerator flues by the waste gases, and become deposited in the flues and regenerator chambers. In operating regenerative open-hearth furnaces it also frequently happens that the slag will boil over into the furnace ports and enter the furnace flues connecting the ports and regenerator chambers.

The accumulations of slag and finely divided materials in the flues lessen the efficiency of the furnaces, and occasion frequent delays in the operation of the furnace in order to remove the accumulated materials, which are highly heated when entering the flues. In order to lessen the frequency of cleaning the flues and regenerator it is common practice to enlarge the horizontal flues leading from the regenerator chambers to the furnace so as to form what are termed slag pockets. These flues or slag pockets are of sufficient size to hold a large quantity of slag and trapped solids and not require cleaning except after long time intervals.

However, use has shown that the enlarged slag pockets lessen the efficiency of the furnace, since the gases and products of combustion passing into these enlarged pockets enroute from and to the regenerators are suddenly expanded, with the resulting loss in energy due to the sudden expansion. In consequence the velocity of the gases is correspondingly reduced. Also slowing of the velocity of the gases and consequent cooling increases this loss by the reduction in volume of gas, so that the gases enter the furnace and the regenerators at

a much lower rate than will occur when the loss of energy is prevented in furnaces embodying my invention.

One object of my invention is the provision in a regenerative furnace of slag pockets of such size and contour as will not materially decrease the velocity of the incoming gases and outgoing products of combustion passing therethrough.

Another object of the invention is to construct the slag pockets in a highly novel manner whereby the slag and other materials deposited therein will be rapidly cooled, so as to permit of their ready removal and make their removal much less laborious.

Still another object of my invention is to construct a slag pocket of the improved design and novel combination of parts described in the following specification and illustrated in the accompanying drawings, in which:—

Figure 1 is a longitudinal sectional elevation showing one end of a regenerative furnace having slag pockets constructed in accordance with this invention.

Figure 2 is a sectional end elevation of the furnace shown in Figure 1, the section being taken on the line II—II of Figure 1.

Figure 3 is a sectional end elevation similar to Figure 2, the section being taken on the line III—III of Figure 1.

Figure 4 is a sectional plan on the irregular line IV—IV of Figure 1, showing the arrangement and location of the flues relative to the end of the furnace and the furnace regenerators, the refractory material on top of the metal floor being omitted for the sake of clearness.

In the accompanying drawings, which show one end of a regenerative open-hearth furnace, the numeral 2 designates the furnace hearth, and 3 the air port in the end of the furnace hearth which connects the hearth 2 with the upper end of vertical air flues 5, 5. The end of the furnace also has a central gas port 4 which connects the ends of the hearth 2 with the vertical gas flue 6. The lower ends of the air flues 5 open into the top of an enlarged horizontal flue 7 which forms a slag pocket for the air flues, and the lower end of the middle vertical flue or gas flue 6 opens into the top of the enlarged horizontal flue forming the slag pocket 8 for the gas flue 6. One end of the slag pocket 7 opens into the air re-

generator 9 and one end of the slag pocket 8 opens into the gas regenerator 10, the other end of these slag pockets being blanked off or closed by bulkheads 20 and 21.

5 A similar arrangement of air and gas ports 3 and 4, vertical flues 5 and 6, and horizontal flues or slag pockets 7 and 8, is employed to connect the other end of the furnace hearth 2 with air and gas regenerators 9 and 10 for that end of the furnace.

10 In each of the slag pockets 7 and 8 is a water cooled bottom wall or floor which may conveniently be raised or spaced above the base of the pocket in order to reduce the 15 size of the slag pocket. As shown, the water cooled floors in the slag pockets 7 and 8 are supported above the base of the pockets by piers 11 arranged along the sides of the pockets. Rails or girders 12, which extend across the width of the pockets, are supported on the piers, and a metal plate 13 is mounted on the rails or girders 12. It will, of course, be understood that when desired the piers 11, girders 12, and plate 13, 20 may be omitted and the water cooled floor supported on brick work built up to the desired height. A loose layer of loam or other finely divided refractory material 14 is placed on top of the plate 13, and a plurality of water cooled pipes 15 are embedded 25 in the loose material 14, (three being shown in the drawings). A refractory covering 16, such as brick, is provided on top of the refractory material 14 and pipes 15. The 30 water cooled pipes 15 which are connected in series, comprise outer pipes or casings 15, which have one, (the inner,) end closed by a suitable plug. The outer ends of the pipes 15, which extend beyond the ends of the slag 35 pockets 7 and 8, are closed by a T or other suitable fitting 17 having end and branch openings for the connection of smaller pipes. A smaller pipe 17' is inserted in each of the pipes 15 through a plug in one end of 40 the fittings 17, the inner end of each pipe 17' extending to a point adjacent to the inner end of a pipe 15. The outer end of the pipe 17' in one of the outside pipes 15 is adapted to be connected to a suitable 45 source of water supply, while the outer ends of the other two pipes 17' are connected by fittings 18 to the branch openings in the fittings 17 on the other pipes so as to cause a continuous flow of water from the source 50 of supply through the pipe 17' in the first tube or pipe 15, then out through the branch opening in the fitting 17 on said tube through the connection 18 to the pipe 17' of the next tube 15, and so on until the last 55 tube is reached, when the water will flow out through a pipe 19 connected to the branch opening in the fitting 17 of said tube to a suitable drain.

60 A suitable bulkhead 20 is built in the slag pocket 8 which extends from the water

cooled floor to the top of the slag pocket, this bulkhead being on a line with the sides of the vertical gas flue 6 farthest from the regenerators so as to prevent the gases flowing beyond such vertical flue. The bulkhead 70 20 also serves to limit the size of the slag pocket so that the gases passing therethrough will not have room to expand to any appreciable extent. A second bulkhead 75 21 may be built at the outer end of the water cooled floor of the slag pocket 8 on a line with the side wall of the furnace when considered necessary or desirable.

80 The space below the water cooled floor is shut off from the regenerators by a wall 23 so that the gases will not escape under said floor.

85 With this improved form of slag pocket the velocity of the gases will not be lessened to any appreciable amount in passing therethrough, and the water cooled floor will quickly cool deposits of slag and other materials, thus reducing the heat radiated from such deposits, and so protecting the brick work. The deposits of slag being rapidly 90 cooled within the slag pockets, are prevented from fusing into solid masses and are cooled to such an extent as to be readily removable during the ordinary week-end 95 shut-downs of the furnace, in this way avoiding and preventing delays in operating the furnace.

98 The advantages of my invention will be appreciated by those skilled in the art.

100 While only one specific form of the invention has been described and shown, the invention is not limited thereto, since various modifications may be made without departing from the scope of the invention as defined in the appended claims.

105 I claim:

1. A regenerative furnace having a regenerator connected therewith, a slag pocket between the hearth of said furnace and said regenerator, an elevated floor above the bottom of said slag pocket, and cooling means embedded in said floor.

110 2. A regenerative furnace having a regenerator connected therewith, a slag pocket between the hearth of said furnace and said regenerator, an elevated floor above the bottom of said slag pocket forming an air space under said floor, and cooling means embedded in said floor, and means for causing circulation of a cooling medium in said 115 cooling means to cool slag deposited on said floor.

120 3. A regenerative furnace having a hearth, a regenerator connected therewith, a slag pocket between said hearth and said regenerator, a plurality of piers extending upwardly from the bottom of said slag pocket and an elevated floor carried by said piers, said floor including a floor plate, water 125 cooled tubes mounted on said plate and a 130

refractory covering for said tubes, and means for circulating water through said tubes.

4. A regenerative furnace having a hearth, 5 a regenerator connected therewith, a slag pocket between said hearth and said regenerator, a plurality of piers extending upwardly from the bottom of said slag pocket and an elevated floor carried by said piers, 10 said floor including a floor plate supported on said piers, a covering of loose refractory material on said plate and water cooled pipes embedded in said loose refractory material, and means for circulating water 15 through said pipes.

5. A regenerative furnace of the open-hearth type, having gas and air ports at each end of the hearth of said furnace, slag pockets formed below said ports, gas and 20 air flues connecting said pockets with their respective air and gas ports, gas and air regenerators on one side of said slag pockets, means connecting said slag pockets and said regenerators, and an elevated floor above 25 the bottom of said slag pockets, cooling means embedded in said elevated floor, and means for circulating a cooling medium through said cooling means to lessen the temperature of solids deposited thereon by 30 the gases flowing through the slag pockets. 6. A regenerative furnace of the open-hearth type, having gas and air ports at each end of the hearth of said furnace, slag pockets formed below said ports, flues connecting 35 said slag pockets with their respective air and gas ports, gas and air regenerators at one side of said slag pockets, means connecting said slag pockets and said regenerators, a bulkhead formed in the gas 40 slag pocket at a point just beyond the flue

connecting said gas slag pocket with said gas port, a plurality of piers forming vertical supports from the bottom of the pockets, a plate member supported on said vertical supports, an intermediate layer of loose 45 refractory material on said plate, a plurality of water circulating tubes embedded in said refractory material, and a covering over said loose refractory material.

7. A slag pocket floor spaced above the 50 bottom of said pocket comprising a supporting structure, a layer of loose refractory material, a series of lengthwise separated pipes embedded in said refractory material, and means connected to said pipes for 55 circulating a cooling medium therethrough.

8. The combination with a regenerative open-hearth furnace of a slag pocket having a plurality of piers forming vertical supports extending upwardly from the bottom 60 of said slag pocket, and an elevated floor on said supports, said floor comprising a plate member, an intermediate layer of finely divided refractory material on said plate, a plurality of water circulating tubes 65 embedded in said refractory material, a refractory covering over said finely divided refractory material, and means for supplying water to said pipes.

9. The combination with a regenerative 70 open-hearth furnace of a slag pocket having a bottom and a floor of refractory material spaced above said bottom, said floor having a series of water cooled pipes embedded in said refractory material, and 75 means for circulating water through said pipes.

In testimony whereof I have hereunto set my hand.

SAMUEL G. WORTON.
